UNITED STATES PATENT OFFICE.

JEANNETTE S. BRIERLY, OF PELHAM, NEW YORK.

SHIRTWAIST-BELT.

1,331,557.

Specification of Letters Patent. Patented Feb. 24, 1920.

Application filed July 29, 1919. Serial No. 314,067.

To all whom it may concern:

Be it known that I, JEANNETTE S. BRIERLY, a citizen of the United States, and a resident of Pelham, in the county of Westchester and State of New York, (whose post-office address is 124 6th avenue, Pelham, New York,) have invented certain new and useful Improvements in Shirtwaist-Belts for Women, of which the following is a specification, taken in connection with the accompanying drawing, which forms a part of the same.

My invention relates to shirt waist belts for women and more particularly to shirt waist belts as separate articles of manufacture which can be sold as such at any dry goods store.

It is the common practice for women who wear shirt waists to pin the lower edge of the shirt waist to the corset. This causes the pin or pins to tear the shirt waist, particularly if it is made of silk or some such material. Also in the present practice every time the shirt waist is worn the gathers have to be reformed, and generally elastics have to be replaced, all of which takes time and is an annoyance to the user.

By my invention all these delays and annoyances and damage to the shirt waist are avoided.

30 In the accompanying drawing showing different illustrative embodiments of my invention, the same numerals refer to similar parts in the several figures.

Figure 1 is a side elevation of my improved shirt waist belt shown as a separate article of manufacture.

Fig. 2 is a detail perspective view on an enlarged scale showing the shirt waist secured in the belt.

40 Fig. 3 is a view of a woman wearing one of the belts.

Fig. 4 is a detail perspective view of my belt showing a different manner of securing the shirt waist in the belt.

45 In the illustrative embodiments of my invention shown in the drawing 1 is my shirt waist belt formed preferably of two thicknesses of strong fabric 2 and 3, secured along their lower meeting edges with stitches 5.

50 Secured preferably by the same stitches are one or more tabs, 6, 6, preferably four. These tabs I preferably locate on the belt so that two of them will be in front, as shown in Fig. 3, and two of them in the back.

55 Also the same stitches 5 secure tapes 7, 7 for holding safety pins 8, 8, or other suit-

able means to secure the tabs 6 to the corset 9 of the user.

In this form of my invention the upper meeting edges of the strips 2 and 3 are left open or unsecured.

The user buying one of these shirt waist belts can herself apply it to a shirt waist 10 by inserting the lower edge 11 between the strips 2 and 3 and secure the belt and the shirt waist together, in any suitable manner, as by the row of stitching 12. She would of course first regulate the gathers.

These belts would be made in different sizes. By bringing the center of the back 70 of the shirt waist opposite the center of the belt, before securing the two together, the tabs 6, 6 will always assume their correct positions.

The shirtwaist 10 can then be worn by 75 simply securing the tabs 6 to the corset 9 by means of the safety pins 8. This will not require rearrangement of the gathers each time that the shirtwaist is worn, avoids replacing of elastics, besides protects the shirt- 80 waist from being torn and pulling out, particularly under the arms, which gives an untidy and careless appearance to the user.

My belt 1 can be readily removed from one shirt waist and applied to another simply by 85 ripping the line of stitching 12. It may be left on the shirtwaist until that shirtwaist is worn out, or may be removed at any time.

In some cases I may form my belt 13, Fig. 4 with a plurality of removable fasteners 14, 90 14 which pass through the lower end 11 of the shirtwaist 10 and snap into the sockets 15, 15. The shirtwaist can be easily removed for washing, or to allow the belt to be used with another shirtwaist, by pulling 95 the sockets 15, 15 from the fasteners 14, 14, the same as is done in an ordinary glove fastener.

Having thus described my invention in connection with illustrative embodiments 100 thereof, but not desiring to be limited to the details shown, what is claimed as new and what it is desired to secure by Letters Patent is set forth in the appended claims:

1. A new article of manufacture comprising 105 a shirt waist belt for women, comprising the belt proper with means to receive the shirtwaist, tabs secured to the belt and securing means to secure the tabs to the corset of the wearer.

2. A new article of manufacture comprising 110 a shirt waist belt for women having an

open belt portion to receive the lower edge of the shirt waist, means to secure the shirt waist in the open belt and at the same time close the belt, tabs on the belt, and securing means to secure the tabs to the corset of the user.

3. A new article of manufacture comprising a removable shirt waist belt for women having an open belt portion to temporarily hold the lower edge of the shirt waist, means to temporarily close the belt portion, means to close the lower portion of the belt and at the same time secure the shirt waist tabs carried by the belt, and means to secure the tabs to the corset of the wearer.

4. A new article of manufacture comprising

ing a removable shirt waist belt for women to be used with one or more shirt waists, having a belt portion formed of two layers of material secured along one of their meeting edges and free at their other meeting edge and adapted to receive between them the lower edges of the shirt waist, means to secure the lower edge of the shirt waist in the belt and at the same time secure the other meeting edges of the belt together, tabs secured to the belt portion and safety pins to secure the tabs to the corset of the wearer.

JEANNETTE S. BRIERLY.
